UNITED STATES PATENT OFFICE.

LA ROUX B. GIDDENS, OF TAMPA, FLORIDA.

COMBUSTIBLE-CHARGE-FORMING DEVICE.

1,218,545.

Specification of Letters Patent.

Patented Mar. 6, 1917.

Application filed April 8, 1916. Serial No. 89,845.

To all whom it may concern:

Be it known that I, LA ROUX B. GIDDENS, a citizen of the United States, residing at Tampa, in the county of Hillsborough and State of Florida, have invented certain new and useful Improvements in Combustible-Charge-Forming Devices; and I do hereby declare the following to be a full, clear, and exact description of the invention, such as will enable others skilled in the art to which it appertains to make and use the same.

The present invention relates to improvements in combustible charge-forming devices for internal combustion engines in which kerosene or other low grade fuel may be employed to operate the engine, and in which such fuel will be subjected to heat in a pre-heater or by-pass arranged in communication indirectly with the exhaust manifold or exhaust pipe; and from which the pre-heated fuel is conveyed to a carbureting chamber where the same is atomized and combined with the necessary quantities of air, it being then delivered to the intake manifold of the engine through an automatically operating combined fuel cut-off valve and control intake valve, and circulated through a passage in which are disposed a series of offset baffle plates.

The improved device, as hereinafter more fully described, is preferably employed in conjunction with a light or high grade fuel, such as gasoline, which is utilized to start the engine and maintain its operation for a sufficient time to insure the proper heating of the by-pass or pre-heater through which the kerosene or low grade fuel is to be subsequently passed.

With the foregoing and other objects in view the present invention, as will herein-after more fully appear, consists in the constructions, combinations and arrangements as described and more particularly pointed out in the claims.

In describing my invention in detail reference will be had to the accompanying drawings, wherein like symbols refer to like parts in the several views, and in which:

Figure 1 is a diagrammatic view, with parts shown in elevation and in section, of an improved device as constructed in accordance with the present invention.

Fig. 2 is an enlarged vertical sectional view through the carbureting chamber and associated parts.

Fig. 3 is a cross sectional view through the

pre-heater and taken on the line 3—3 in Fig. 1; and

Fig. 4 is an enlarged view of the swivel mechanism for connecting the control and fuel cut-off valves.

Referring more particularly to the drawings, 1 designates the cylinders of an internal combustion engine, from which the burned gases are conducted through the usual exhaust 2. At 3 is indicated the intake manifold which is in communication with the improved mixing chamber and associated devices, as will be presently described.

Associated with either the exhaust manifold or the exhaust pipe, which is designated generally at 2, is a by-pass or pre-heater, which, in the present instance, advantageously consists of an elongated cylindrical pipe 4 arranged in open circuit with said engine exhaust through nipples 5 and 6. The ends of the pre-heater pipe 4 are inclosed by heads 7 and 8, between which are supported centrally within said pre-heater a hollow sleeve 9, the same forming with the interior wall of the pre-heater an annular chamber for the free circulation of the exhaust gases. By locating the pre-heater 4 without the exhaust 2, the kerosene or other low grade fuel employed is prevented from attaining a high degree of heat, which would transform the same into gas, and by the employment of the hollow sleeve 9 the degree of heat imparted to the liquid kerosene will be further reduced.

Centrally through the hollow sleeve 9 passes a pipe 10 of appreciably smaller diameter, so as not to come in contact with the former but leave an air space therein through which the heat may be transmitted. This pipe 10 is in communication with a kerosene or other low grade fuel supply, which is indicated at 11 as being one compartment of a tank 12 partitioned off by division plate 13, and providing a second compartment 14 for gasoline or other light or high grade fuel; it being understood, however, that the kerosene and gasoline or other fuels employed may be contained in separate tanks which will be located on the vehicle at convenient points.

The gasoline supply compartment 14 is in communication through a pipe 15 with a head 16, the passage therethrough being under the control of a valve 17, which in practice will be arranged to be operated from the dash or instrument board of the vehicle,

The kerosene supply from the pipe 10, after passing through the pre-heater 4, is conveyed by pipe 18 to the head 16, the passage thereof being under the control of a 5 valve 19 similar to the valve 17, and likewise to be controlled in practice from the dash or instrument board of the vehicle.

The head 16 is traversed by a passage 20 formed at one end with a valve seat 21, 10 against which is arranged to close a needle valve 22 also controlled from the dash or instrument board, and which regulates primarily the delivery of both grades of fuel to the carbureting chamber 23, which is contained within a shell or casing 24. In direct communication with the passage 20 in the head 16 is a pipe 25 passing through a flanged plug 26 bolted or otherwise secured, as indicated at 27, to a similarly flanged off- 15 set 28 of the casing 24.

The pipe 25 extends through the plug 26 and into the carbureting chamber 23, where the same is directed upwardly, as indicated at 29, and where it is provided with a valve 25 seat 30. Operating in conjunction with the valve seat 30, as an auxiliary control for the fuel, is a valve 31 carried on the lower end of a stem 32. The stem 32 extends through an open cage 33 threaded or otherwise secured to the valve seat 30, pipe 25, or other part, and forming at its upper end a bearing for one end of a coil spring 34, which encircles the valve stem 32 and normally operates to maintain said valve 31 seated. The 30 valve stem 32 is connected by a swivel 35 with the lower end of a threaded rod 36, which adjustably engages through the hollow threaded lower end of the valve stem 37 of a control intake valve 38. The adjustment, after being made, is secured against possible displacement by lock nut 39 which abuts against a head 40 formed on the lower end of said stem 37. The control valve 38 is yieldingly held against its seat 41 by a coil 45 spring 42 operating against the head 40, as clearly disclosed in Figs. 1 and 2.

In that side of the casing 24 opposite the flanged plug 26 is a flanged offset 43, inclosed by a removable head 44 through which access may be had to the interior of the carbureting chamber 23 for purposes of adjusting the threaded rod 36 in the stem 37, and for making other adjustments, repairs, or replacements of parts, as may be found necessary or desirable.

The lower end of the carbureting chamber 23 is arranged to connect with a pipe 45 through which air from the atmosphere is conveyed from a heater 46, of any suitable 60 type, clamped about the exhaust 2. This heater 46 is in open communication with the atmosphere, through which air may be drawn into contact with the exhaust 2, and thereby become heated prior to delivery 65 through the pipe 45 and to the carbureting

chamber 23, where it encounters the incoming fuel issuing past the valve 31 and through the cage 33.

Surrounding the pipe 25, and disposed preferably between the head 16 and the flanged plug 26, is a coil 47 in circuit with the vehicle storage battery, the closing of such circuit being under the control of a switch also located on the dash or instrument board of the vehicle; the purpose of such coil being to supply the place of the pre-heater or by-pass 4 in case the engine is to be started or initially operated on the kerosene or other low grade fuel. The upper end of the carbureting chamber 23 is inclosed by a threaded cap 48, from which depends a hollow sleeve 49 into which is slidably received the upper end of the stem 37 of the control valve 38.

A control rod 50 extends down within said hollow sleeve 49, and is normally held elevated at a distance above the end of the valve stem 37 by a coil or other spring 51 engaging against the upper face of the cap 48 and a head 52. Such coil spring 51 thus maintains the head 52 in contact with a cam 53 on a rock shaft 54. The rock shaft 54 is provided with an arm 55 connected by a link 56 to mechanism on the dash or instrument board of the vehicle. By operation of such link 56 and arm 55 the shaft 54 may be rocked to bring the lobe of the cam 53 down upon the head 52, and thereby move the control rod 50 against the opposition of the coil spring 51 down into close proximity to the upper end of the stem 37, and thereby limits the upward movement of the valve 38, thus diminishing the air supply.

The arm 55 on the rock shaft 54 is connected by a link 58 to a similar arm 59 on the spindle of a throttle valve 60. The throttle valve 60 is located at the entrance of a tubular extension 61 of the casing 24. The tubular extension 61 is connected to the intake manifold 3 through a four-way coupling 62. Clamped between the union 63 of the extension 61 and the coupling 62 are the flanges 64 of a sleeve 65 disposed within said extension 61, and being provided with staggered baffle plates 66 whereby the incoming charge will be subjected to a zigzag course, such as will have the effect of bringing the air and fuel particles into intimate contact to promote a homogeneous mixture.

The ends of the hollow sleeve 65 are inclosed by gauze heads 67 and 68, which have the effect of finely subdividing the charge particles and effecting a more complete mixture thereof. These gauze heads 67 and 68 have the further effect of preventing the back-fire or false explosion from passing back to the carbureting chamber 23 and other parts of the apparatus. The lower branch 69 of the four-way coupling 62 is formed with a valve seat 70 for receiving a safety valve 71.

The valve 71 carries a stem 72 on which is a head 73. A coil spring 74 encircles the stem 72 and operates between the head 73 and seat 70 so as to make the valve 71 automatic in action. Whenever a pressure in the four-way coupling 62 exceeds the strength of the spring 74, the valve 71 will open and permit the escape of such pressure to the atmosphere.

10 The intake manifold 3, in accordance with the different makes of engines, is connected either to the branch 75, as in the case shown in the present drawings, or to the branch 76 which, in the present instance, is shown covered by a removable plate 77.

The operation of the above described invention may be substantially as follows:

For the initial operation of the engine 1, gasoline or other high grade fuel from the supply tank 14 is permitted to flow through the pipe 15 by opening the valve 17 and needle valve 22. The needle valve 22 being open, admits the gasoline into the head 16, where it flows through the passage 20, into the pipe 25, and therethrough to the carbureting chamber 23, where it is liberated under the control of the valve 31. This valve 31, by means of the connections above described, is operated to open when the suction of the engine unseats the control valve 38. The air valve 38 unseating, the suction will draw in air from the atmosphere through the heater 46 about the exhaust 2 and through the pipe 45 to the carbureting chamber 23, where such heated air will encounter the fuel issuing from the valve 31 and through the cage 33. The combined air and fuel will thereupon pass into the head of the carbureting chamber 23 above the air valve 38, and as controlled by the throttle valve 60 will pass through the hollow sleeve 65 in a tortuous course as compelled by the staggered baffle plates 66, and thence through the coupling 62 and into the intake manifold 3.

The engine 1 is operated on the high grade fuel for such a length of time as is sufficient to attain a reasonably high degree of heat in the pre-heater 4; and when such time has arrived, the valve 17 is closed to cut off the gasoline supply and the valve 19 opened to admit the kerosene from the tank 11. The kerosene will thus be conveyed through the pipe 10, passing through the pre-heater 4, where its temperature will be slightly raised to put it in condition for ready mixture with the heated air in the carbureting chamber 23. From the pre-heater 4 the kerosene passes, by means of the pipe 18 and through the valve 19, to the head 16 in quantities as controlled by the needle valve 22. From the head 16 the kerosene passes through the pipe 25 and into the carbureting chamber 23, where it encounters the heated air in a manner similar

to that described above of the gasoline, and it need not be repeated here.

In case the vehicle operator finds that his supply of gasoline or other high grade fuel is exhausted, the engine 1 may be started on the kerosene by the use of the electric coil 47, which is placed in closed circuit by a switch on the dash or instrument board, and the same then operates substantially in the capacity of the pre-heater 4 to raise the temperature of the kerosene to a point where it will readily volatilize and combine with the air in the carbureting chamber 23.

While I have illustrated in the accompanying drawings and described above the various constructions, combinations and arrangements of parts, I do not desire to be limited to any such features of construction except as may be required by the appended claims.

I claim:

1. In a combustible charge forming device, the combination of a casing, a fuel supply in communication with said casing, an air supply also in communication with said casing, a carbureting chamber within said casing, a fuel cut-off valve located in said casing, a control valve above said carbureting chamber, means for connecting said control and cut-off valves including a swivel connection, and means for regulating the throw of said control valve, substantially as described.

2. In a combustible charge forming device, the combination of a casing providing a carbureting chamber, a fuel supply in communication with said chamber, an air supply also in communication with said chamber, a fuel cut-off valve in said casing, a control valve disposed in said casing, spring means for seating said cut-off and control valves, a swivel connection uniting said valves for simultaneous opening, and means for regulating the throw of said control valve, substantially as described.

3. In a combustible charge forming device, the combination of a casing providing a carbureting chamber, fuel supplies arranged in communication with said carbureting chamber, an air supply also in communication with said chamber, a fuel cut-off valve in said casing, a stem for said valve, a control valve, a stem projecting from said control valve, a rod connected to said last-named stem, a swivel joining said rod and first-named valve stem, spring means for normally seating said valve, and means for regulating the throw of said control valve, substantially as described.

4. In an improved combustible charge forming device of the character described, the combination of a casing providing a carbureting chamber, a fuel supply in communication with said casing, an air supply also in communication with said chamber,

a fuel cut-off valve in said chamber, a control valve associated with said cut-off valve, connections between said valves for actuating the cut-off valve to open when the control valve is moved from its seat, means for regulating the throw of said control valve including a stem on said control valve, a rod adjustable relatively to said stem, cam means for adjusting said rod, and spring means for maintaining said rod in contact with said cam, substantially as described.

5. In a combustible charge forming device of the character described, the combination of a casing, a carbureting chamber located within said casing, a fuel supply, means placing said fuel supply in communication with said chamber, an air supply also in communication with said chamber, a fuel cut-off valve, a stem on said valve, a control 10 valve operable by the engine suction, stems projecting from said control valve, a rod coupled to one stem, a swivel uniting said rod and cut-off valve stem, a sleeve slidably receiving the other of said control valve 15 stems, a rod movably mounted in said sleeve and adapted to engage the control valve stem and limit the movement of the control valve, a cam for adjusting said rod, and spring means for holding said rod in contact 20 with said cam, substantially as described.

6. In a device of the character described, the combination of a casing, a carbureting chamber formed within said casing, a fuel supply, means placing said fuel supply in communication with said carbureting chamber, an air supply also in communication with said carbureting chamber, means for heating the air, a fuel cut-off valve in said 25

casing, a control valve, connections between said control and cut-off valve including the 40 swivel, means for regulating the throw of said control valve, a head disposed beyond said carbureting chamber, an extension on said casing communicating with said head and arranged to be connected to the engine 45 intake, a throttle valve in said extension, means connecting said throttle valve and control valve regulator for simultaneous operation, and a homogenizer in said extension beyond said throttle valve, substantially 50 as described.

7. In a device of the character described, the combination of a casing, a carbureting chamber provided within said casing, low and high grade fuel supplies in communication with said carbureting chamber, a heater for said low grade fuel supply, an air supply in communication with said carbureting chamber, means for heating said air, a cut-off valve in said casing, spring 60 means for seating said valve, a control valve, spring means for seating said control valve, connections between said valves including a swivel, means for regulating the throw of said control valve, a head formed on said 65 casing beyond said carbureting chamber, an extension communicating with said head and adapted to be connected to the engine intake, a throttle valve in said extension, means for connecting said throttle valve and control valve regulator for simultaneous operation, and a homogenizer in said extension, substantially as described.

In testimony whereof, I affix my signature.

LA ROUX B. GIDDENS.
